SPARK PLUG

Leo J. McKone, Chicago, Ill., assignor of one-half to Dean D. Francis, Cleveland, Ohio, and one-eighth to Kenneth E. Lyman, Chicago, Ill.

Application July 17, 1935, Serial No. 31,804

6 Claims. (Cl. 123—169)

This invention relates to a spark plug and more particularly to a spark plug wherein the electrodes define a spark gap of varying width.

In the usual spark plug employed in internal combustion engines, the surfaces defining the spark gap are parallel to each other to provide a spark gap of constant width. Such an arrangement does not compensate for the varying intensities of the spark at different speeds of the engine. At low speed, for instance, when the mixture is rich and the compression low, a "fat" spark would be desirable, whereas at high speed, with the mixture lean and compression high, the spark is then weaker, so that a narrower spark gap would be desirable.

I have now found that greater ignition efficiency can be obtained under these conditions by providing a spark gap of varying width. With such a spark gap, when the engine is operating at low speed and the mixture is rich, the ignition coil can give a fat spark that will more efficiently ignite the overly rich mix. However, at high speeds, when the mix is lean and compression is high, the spark is then weaker due to low saturation of the primary windings in the ignition coil and with my varying width spark gap, the spark finds a narrower gap to jump across.

It is therefore an object of this invention to provide a spark plug having a spark gap of varying width, whereby the ignition efficiency of the spark plug is increased.

It is a further important object of this invention to provide a spark plug wherein the electrode wires present convergent surfaces defining a spark gap of varying width to compensate for varying intensities of spark at different engine speeds.

Other and further important objects of this invention will be apparent from the disclosures in the specification and the accompanying drawings.

This invention (in a preferred form) is illustrated in the drawing and hereinafter more fully described.

On the drawing:

Figure 1 is an elevational view, partly in section, of a spark plug embodying the principles of my invention.

Figure 2 is a fragmentary elevational view taken substantially along the line II—II of Fig. 1.

Figure 3 is a sectional view taken substantially on the line III—III of Fig. 1.

Figure 4 is a fragmentary sectional view of a modified form of my invention.

Figure 5 is a further modified form of my invention.

As shown on the drawing:

The reference numeral 10 indicates generally a spark plug embodying the principles of my invention and comprising the usual shell 11, insulated core 12 and externally threaded skirt 13, adapted to be threaded into the engine block. An electrode wire 14 extends beyond the lower end of the core 12 and is coaxial with the plug. Said wire is of circular cross section and terminates in a plane end face 15 normal to the axis of the wire.

The skirt 13 is provided with an extension 16, angularly offset therefrom and connected thereto by a neck portion 17 of reduced cross sectional area. The purpose of reducing the cross sectional area of the metal connecting the extension 16 with the skirt 13 is to reduce the amount of heat flowing from the extension 16 to the skirt 13 and thus concentrate the heat to a greater extent in said extension.

A second electrode wire 18 is secured at one end in the extension 16 and extends in the plane of the wire 14 and at an angle thereto provide a spark gap, indicated at 19, of varying width. The angle between the electrode 18 and the electrode 14 is not a right angle, as is customary in heretofore known spark plug constructions, so that the longitudinal surface of the wire 18 forms a small acute angle with the plane surface of the wire end 15. There is thus provided a spark gap of varying width that permits the spark to jump across at the wider or at the narrower point depending upon the condition of the ignition coil.

In Fig. 4, a laterally extending electrode 20 is secured at one end in the bottom portion of a skirt 21 and projects at right angles to a core electrode 22. The free end of the electrode 20 is beveled as at 23 to provide a spark gap 24 of varying width between the plane lower end of the electrode 22 and the tapered flat surface 23 of the electrode 20.

In Fig. 5, there is a reversal of parts, in that the vertical electrode 25 is provided with a tapered or beveled flat end face 26 and the laterally extending electrode 27 projects at right angles to the axis of the electrode 25 to provide a spark gap 28 of varying width between the two electrodes.

It will thus be apparent that all of these various forms of my invention embody the same principle of a varying width spark gap. The variation in the width of the spark gap at vari-

ous points will depend upon many factors but in general the minimum width will be in the neighborhood of 0.020 inch and the maximum width in the neighborhood of 0.032 inch. This variation in width permits an automatic compensation for the variations in the intensity of the ignition coil current at different engine speeds. Thus, when the engine speed is slow and the mixture is rich, the spark being more intense can jump through the greater distance provided by the varying spark gap, and when the engine speed is high and the intensity of the spark weak, the spark can jump across the narrow width.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. In a spark plug, a pair of angularly disposed electrodes lying in substantially the same plane, a flat end surface of one electrode and a 25 tapered flat surface on the other electrode defining a spark gap of varying width.
2. In a spark plug, a pair of electrode wires, one of said wires extending axially of the plug and having a beveled flat end face and the other 30 of said wires extending substantially at right angles to the first wire.
3. In a spark plug, a pair of spaced electrode wires, one of said wires extending axially of said plug and having a flat end surface, and the other

of said wires extending at an angle to said first wire to present a surface convergent with respect to said flat end surface for defining a spark gap of varying width.

4. A spark plug comprising a coaxial electrode wire having a normal plane end face, a threaded skirt surrounding said wire and having an extension beyond said wire end face, said extension being joined to said skirt by a neck portion of reduced cross sectional area, and a second electrode wire secured in said extension and extending in non-parallel relation to the plane of said end face to define a spark gap of varying width. 5

5. A spark plug comprising a shell having a depending skirt portion with an extension below 15 the bottom of the skirt, said extension being joined to the skirt by a neck portion of reduced cross-sectional area, an electrode wire secured in said extension below the neck portion thereof and extending transversely along the bottom of 20 the plug, a second electrode wire extending axially within the shell of the plug, an end surface of one electrode and a longitudinal surface of the other electrode defining a spark gap of varying width. 25

6. A spark plug comprising a shell having a depending skirt portion with an extension below the bottom of the skirt, said extension being joined to the skirt by a neck portion of reduced cross-sectional area, and an electrode wire secured at its end in said extension below the neck portion thereof. 30
